(57) **CLAIM**

The ornamental design for a device for reproduction of sound, as shown and described.

DESCRIPTION

FIG. 1 is a perspective view of a device for reproduction of sound showing our new design;

FIG. 2 is a front side elevational view of the device for reproduction of sound of FIG. 1;

FIG. 3 is a rear side elevational view of the device for reproduction of sound of FIG. 1;

FIG. 4 is a right side elevational view of the device for reproduction of sound of FIG. 1;

FIG. 5 is a left side elevational view of the device for reproduction of sound of FIG. 1;

FIG. 6 is a top plan view of the device for reproduction of sound of FIG. 1; and,

FIG. 7 is a bottom plan view of the device for reproduction of sound of FIG. 1.

The broken lines shown in the drawings illustrate portions of the device for reproduction of sound that form no part of the claimed design.

1 Claim, 4 Drawing Sheets
